UNITED STATES PATENT OFFICE.

CARL BRUNO SANDER, OF CHEMNITZ, GERMANY.

KNITTING-MACHINE.

SPECIFICATION forming part of Letters Patent No. 512,059, dated January 2, 1894.

Application filed June 26, 1893. Serial No. 478,828. (No model.)

To all whom it may concern:

Be it known that I, CARL BRUNO SANDER, of Chemnitz, Saxony, Germany, have invented a new and Improved Knitting-Machine, of 5 which the following is a full, clear, and exact description.

The invention relates to warp knitting machines, and its object is to provide a machine, which is simple and durable in construction, 10 very effective in operation, and arranged to wind a band, braid, cord, or like article around some of the pattern threads.

The invention consists of a revoluble pattern thread and band carrier journaled in a 15 sliding bearing.

The invention also consists of certain parts and details and combinations of the same, as will be fully described and then pointed out in the claims.

Reference is to be had to the accompanying drawings forming a part of this specification, in which similar letters of reference indicate 20 corresponding parts in all the figures.

Figure 1 is a plan view of part of the improvement. Fig. 1^a is a continuation thereof. Fig. 2 is a side elevation of part of the improvement. Fig. 2^a is a continuation thereof. Fig. 3 is an enlarged front elevation of the revoluble thread and band carrier and 25 adjacent parts. Fig. 4 is a plan view of the same. Fig. 5 is an enlarged cross section of the improvement on the line 5—5 of Fig. 1. Fig. 6 is a cross section of part of the improvement on the line 6—6 of Fig. 3. Fig. 7 is an enlarged section of the thread and band 30 carrying cylinder. Figs. 8, 9, 10, 11, and 12, are inverted plan views of the same in different positions. Fig. 13 is an enlarged front elevation of a piece of the fabric formed by 35 the machine. Fig. 14 is a rear elevation of the same; and Figs. 15, 16, 17, 18 and 19 are enlarged side elevations showing the formation of the fabric.

The improved knitting machine is provided 40 with a suitably constructed frame A, on which is mounted to reciprocate the needle bar B, carrying the knitting needles C and adapted to be operated in the usual manner by a suitable mechanism from the main driving 45 shaft D, as is plainly illustrated in Figs. 1 and 5. The knitting needles C operate in

conjunction with the eyes E held on the usual sliding and up-and-down swinging bar E', the said needles and eyes operating with the binding thread F and the pattern threads F' and F² in the usual manner, to form the desired fabric. In addition, however, the pattern threads F' are wound, previously to the knitting with threads F and F², with a band, cord, braid or like article F³, as hereinafter 55 more fully described and plainly illustrated in the drawings. The binding threads F are carried to the eyes E in the usual manner from suitable spools supported on a rack, not shown, but the threads F' and F² and the 60 band F³ are fed from above in such a manner that the threads F² pass to the needles C in the succession prescribed by the particular pattern it is desired to produce, while the pattern thread F' and band F³ are fed through 65 a revoluble pattern thread and band carrier 70 G supporting, at its lower end and on diametrically opposite sides, the vertically disposed eyes H and I held on rods H' and I' respectively, secured by set screws H² and I² 75 respectively in the wall of the cylindrical carrier G. The eye I is elongated, as is plainly shown in Figs. 8 to 12, so as to permit of the convenient passage of the flat braid, band or cord F³, while the other eye H is circular, for the 80 passage of the usual pattern thread F'. The carrier G is preferably made in the shape of a vertically-disposed cylinder journaled in a bearing J' attached to the front face of a bar J mounted to slide longitudinally in bearings 85 A' and A² secured to the frame A, as is plainly illustrated in Fig. 1. On the upper end of the carrier G is arranged a gear wheel G' in mesh with a rack K' formed on the front edge of an L-shaped slide K fitted to slide on the bar 90 J and provided for this purpose on its vertical member with longitudinally extending slots K², see Figs. 3 and 6, through which pass screws K³ screwing in the bar J at the rear thereof. Between the heads of the set 95 screws K³ and the rear face of the slide K are interposed springs K⁴, so as to prevent accidental displacement of the slide K on the bar J. At the rear of the bar J is arranged a second bar L also mounted to slide longitudinally in the bearings A' and A², and provided 100 at its middle with a vertically slotted exten-

sion L' engaged by a pin K⁵ secured to the slide K to permit a lifting of the bar J without interfering with the bar L, it being understood that both bars are free to move upward in their bearings A' and A², as will be readily understood by reference to Fig. 5, the said bars being pressed down in the said bearings by springs A³. A longitudinal sliding motion is given to the bar J, and consequently to the carrier G journaled thereon, by sets of pins N and N' held on endless chains O and O' respectively, adapted to receive a traveling motion and also adapted to be moved longitudinally toward and from the bar J, as illustrated in Figs. 1 and 2. The individual pins of the sets of pins N and N' are of varying lengths, and are adapted to engage plates J² and J³ respectively, secured on the ends of the bar J. The other bar L is likewise provided at its ends with plates L² and L³ adapted to be engaged by sets of pins N² and N³ also secured on links of the traveling and sliding chains O and O' respectively, it being understood that the corresponding pins N and N² of the chain O impart a sliding motion to the bars J and L, to the right, while the other corresponding pins N' and N³ of the chain O' impart a sliding motion to the said bars J and L to the left whenever the said chains O and O' receive the proper motion from the driving shaft D. As I do not claim the mechanism for imparting a sliding motion to the bars J and L, a further detailed description of the same is not deemed necessary. An up-and-down sliding motion is given to the bar J by the arms P and P' secured on the transversely extending shafts P² and P³ respectively, journaled in extensions formed on the bearings A' and A², as is plainly shown in Figs. 1 and 2. The front ends of the shafts P² and P³ carry the crank arms Q and Q' respectively, connected with each other by a link Q², so that the rocking motion given to one shaft is transmitted by the said crank arms Q' and Q and the link Q² to the other shaft, whereby both arms P and P' swing simultaneously upward or downward to raise or lower the bar J. In order to impart this rocking motion to one of the shafts P² and P³, I provide the latter with a crank arm Q³ carrying a friction roller Q⁴ adapted to be engaged by a cam R secured on a gear wheel R' connected by a suitable intermediate train of gear wheels with the main driving shaft D, so that the rotary motion of the latter causes a rocking of the said shafts for the purpose hereinafter more fully described. When the needles C move into a rearmost position, as shown in Fig. 1, then the pattern thread and band carrier G is in the position shown in Figs. 8 and 15, but previous to the needles passing into this rearmost position, the bar J carrying the carrier G is lifted by the swinging action of the arms P, P', and thereby the eyes H and I are lifted sufficiently above the needles C so that the latter are not touched by the eyes H and I at the time the carrier is moved longitudinally. The bar L is now shifted from left to right by the action of the corresponding pin N² while the bar J at first remains stationary. On shifting the bar L, and before the bar J begins to move the pin K⁵ is carried along to the right by the extension L', so that a sliding motion is given to the slide K and the rack K' thereof rotates the gear wheel G' and consequently gives a three-fourths revolution to the carrier G, so as to change the position of the eyes H and I from that shown in Figs. 8 and 15 to that illustrated in Figs. 9 and 16, the carrier revolving in the direction of the arrow a'. The pattern thread F' and the band F³ in the said eyes H and I, respectively, are carried along by the said eyes so that a double twist is given to the band as illustrated in Fig. 16. As the chain O continues to slide to the right, the shorter pin N engages the other bar J and imparts a sliding motion to latter from the left to the right, the two bars L and J, move simultaneously, and the needles C bind the pattern threads F' in the usual manner during the displacement of the bar J, the latter and the bar L, stopping simultaneously at the end of their strokes, caused by the sliding of the chain O, to the right. Previous to the next shifting of the bars J and L, from left to right, the chain O is carried back to the left by its operating mechanism, so as to cause one of the pins O² to engage the stationary stop O³ and thereby partly turn the roller O⁴ of the chain O and bring the next pins N and N² respectively, into an operative position. The chain O then again moves to the right, and the pins N² and N being of the required lengths, successively act on the bars L and J, as before described, to first turn the carrier G and cause the same with the band F³ and thread F' to assume the position shown in Figs. 10 and 17; and thereafter the bars L and J move in unison to permit the needles C to bind the pattern threads F'. It is understood that when the bars J and L move from left to right, the chain O' is in an outermost position to permit a free shifting of the said bars, and when the latter are moved from right to left by the chain O', then the other chain O is in an outermost position. On shifting the bars J and L from right to left a turning of the carrier G takes place, but in an opposite direction from that above described, the carrier then turning in the direction of the arrow b', Figs. 10 and 11. It will be understood that the movements of the carrier G during the shifting of the bars L and J to the left correspond exactly to the movements which take place during the shifting of the said bars to the right, that is to say, the carrier G is first given a partial rotation, which brings it into the position illustrated by Figs. 11 and 18, and then, after the bar J has been moved to the left, the carrier is again given a partial rotation in the same direction, and the bar J is moved farther to the

left, whereby the parts are caused to assume the position shown in Figs. 12 and 19. It is understood that by the turning of the carrier in opposite directions, the band F³ is placed all around the thread F' to appear on both sides of the pattern, and from left to right, and then from right to left. It is further understood that the movements of the carrier G and the bar J may be performed in a different succession from that above described, but in any event, the rotation of the carrier will preferably be an intermittent one. At the end of the stroke of the bars J and L to the left, the carrier G and eyes H, I, are in the position shown in Figs. 12 and 19, corresponding to those shown in Figs. 8 and 15, that is, the one at the beginning of the operation.

Having thus described my invention, I claim as new and desire to secure by Letters

20 Patent—

1. A knitting machine provided with a revoluble pattern thread and band carrier jour-

naled in a sliding bearing, substantially as shown and described.

2. In a knitting machine, the combination, 25 with two bars mounted to slide longitudinally and means for raising and lowering one of the said bars, of a rack fitted to slide on the vertically movable bar and actuated by the other bar, and a pattern thread and band carrier 30 in mesh with the said rack and journaled on the bar carrying the rack, substantially as shown and described.

3. A knitting machine provided with a revoluble pattern thread and band carrier jour- 35 naled in a sliding bearing, and means, substantially as described, for imparting intermittent rotary motions, and in opposite directions, to the said carrier, substantially as shown and described.
